UNITED STATES PATENT OFFICE.

ANDREW P. GOSNELL, OF LOS ANGELES, CALIFORNIA, ASSIGNOR OF ONE-HALF TO
HARRY E. BELL, OF LOS ANGELES, CALIFORNIA.

SHINGLE AND ROOF CONSTRUCTION.

1,086,524.

Specification of Letters Patent.

Patented Feb. 10, 1914.

Application filed December 11, 1912. Serial No. 736,164.

To all whom it may concern:

Be it known that I, ANDREW P. GOSNELL, a citizen of the United States, residing at Los Angeles, in the county of Los Angeles, State of California, have invented new and useful Improvements in Shingles and Roof Constructions, of which the following is a specification.

This invention relates to an improved shingle and the roof construction made with my improved shingle; and the prime object of the invention is the provision of cementitious shingle in such form, and capable of being made into a roof in such manner, as to be immune to breakage such as is common to shingles of this class.

In my improved form of shingle I preferably attach each shingle to the sheathing only at the upper end, (through the medium of a projecting flexible securing member, preferably the projecting end of an internal reinforce, which projects beyond the upper or thin end of the shingle). The body of the shingle I do not attach at all to the sheathing; but I interconnect the shingles of each course in such manner that, in order to raise one shingle, all of the shingles above it on the roof must also be raised. This construction provides that the shingles shall not be under any strain which would be liable to cause their fracture; and it is this peculiarity of construction which I wish to explain in detail in the following specification and to secure to myself in the appended claims, reference being had to the accompanying drawings, in which:

Figure 1 is a perspective, showing a portion of a roof construction with my improved shingle. Fig. 2 is a longitudinal section of my shingle. Fig. 3 is a fragmentary detail showing an approved method of interconnecting the shingles of each course. Fig. 4 is a section showing a different form of sheathing and attachment.

Referring now to the drawings, 5 designates any suitable form of sheathing, which forms the foundation of my roof construction. My shingles 6 are placed thereon in the relative position common to shingled roofs, each shingle consisting of the cementitious body, and each having a flat, preferably mesh, reinforce 8 therein, the reinforces projecting from the thin or upper end of the shingle as is illustrated at 8^a. The extent of the reinforces within the shingle may be

varied according to requirements; but, in general, it will be sufficient to provide ample reinforcement for the entire shingle. The reinforces may be made of any suitable material, preferably open mesh metallic substance, and preferably of suitable wire netting.

When nailing the shingles on a roof I attach them to the sheathing solely by attaching the projecting reinforcements thereto. 65 This attachment may be effected by nails 9 or in any other suitable manner. The shingle is not attached at any other point to the sheathing; being allowed to rest in place by its own weight and being under no strain, 70 such as would be imposed by resting upon two or more pieces of the sheathing and being drawn down tightly in its center by a nail or other securing device.

I preferably attach the shingles of each 75 course together by a suitable means on the longitudinal edge of each shingle. This means may consist in an eye 10 and a tongue 11 to fit therein, or by any other suitable and substantial and easily handled arrangement. 80 The eye may be recessed in the edge of the shingle, as shown in a portion of Fig. 3. This attachment provides that any shingle can not be raised without raising also the adjacent shingles of the course; and the 85 shingles of any course can not be raised without also raising the shingles above. It consequently requires a great or abnormal force to raise the shingles in my roof construction; greater force than would ever be 90 exerted by wind pressure or the like.

The features which I wish to emphasize and secure to myself in the following claims are, first, the sole attachment of the shingle through the medium of the flexible securing 95 member (preferably the projecting end of its internal reinforce), and then in combination, the means for attaching together the shingles of each course.

In Fig. 4, I have shown an entirely fire-proof construction the same being made up of angle iron sheathing 100 and my cementitious shingle 102. Here the reinforcement 103 is bent around the angle iron 100 and held securely thereby.

Having described my invention, I claim:

1. A roofing construction, comprising a foundation sheathing, a plurality of shingles laid in superimposed courses, each shingle comprising a cementitious body, a flexible

metallic member embedded within said body to form a reinforce therefor and projecting from one end of said body to form a flexible securing member, means for fastening each shingle to the sheathing consisting solely of means fastening said flexible securing member to the sheathing, whereby the shingles are flexibly secured to the sheathing, and means for securing the shingles of each course together below their upper ends, substantially as described.

2. A roofing construction, comprising a foundation sheathing, a plurality of shingles laid in superimposed courses, each shingle 15 comprising a cementitious body, a flexible metallic member embedded within said body to form a reinforce therefor and projecting from one end of said body to form a flexible securing member, means for fastening each shingle to the sheathing consisting solely of means fastening said flexible securing mem-

ber to the sheathing, and coöperating means on the shingles of each course for securing the shingles of each course together.

3. A roofing construction, comprising a 25 foundation sheathing, a plurality of shingles laid in horizontal courses, each shingle comprising a cementitious body, means for flexibly attaching each shingle exclusively at its upper end to the sheathing; whereby each 30 shingle is free to rise and fall at its lower end, and means for attaching together the shingles of each course at points below their upper ends.

In witness that I claim the foregoing I 35 have hereunto subscribed my name this 5th day of December 1912.

ANDREW P. GOSNELL.
